Primary Examiner—Doris Clark*Attorney, Agent, or Firm*—Steven P. Shurtz; Willian Brinks Hofer Gilson & Lione[57] **CLAIM**

The ornamental design for a border edge, as shown and described.

DESCRIPTION

FIG. 1 is a perspective view of a border edge showing my new design;

FIG. 2 is a front elevational view thereof;

FIG. 3 is a top plan view thereof;

FIG. 4 is a bottom plan view thereof;

FIG. 5 is a side elevational view thereof, with the opposite view being a mirror image; and,

FIG. 6 is a rear elevational view thereof.

The broken line showing of ground pegs is for illustrative purposes only and forms no part of the claimed design.
